UNITED STATES PATENT OFFICE

2,547,062

ELECTROMAGNETIC RELAY

Stanley Herbert Towner and Percy Arthur Childs, London, England, assignors, by mesne assignments, to International Standard Electric Corporation, New York, N. Y., a corporation of Delaware

Application May 30, 1945, Serial No. 596,680
In Great Britain April 28, 1944

Section 1, Public Law 690, August 8, 1946
Patent expires April 28, 1964

3 Claims. (Cl. 200—104)

1

This invention relates to electromagnetic relays. Among the objects of the invention is that of providing a more robust design of electromagnetic relay, and especially a midget relay.

The following description relates to the accompanying drawings, in which:

Fig. 1 is a side-view of a complete relay in accordance with the present invention;

Fig. 2 is a side-view of the contact-spring-set assembly;

Fig. 3 is a left-hand end view of the spring-set assembly shown in Fig. 2;

Fig. 4 is an underneath plan view of the spring-set assembly shown in Fig. 2;

Fig. 5 is a top plan view of the armature;

Fig. 6 is a side view of the armature;

Fig. 7 is a section on the line A—A of Fig. 5;

Fig. 8 is a left-hand end view of a relay, being a modification; and

Fig. 9 is a similar view of a further modification.

The design of the relay is somewhat like that disclosed in the copending U. S. patent application Ser. No. 546,545, now Patent No. 2,501,157, June 6, 1950. The relay winding 1 is mounted upon a soft-iron core 2 of which the forward projecting end 3 is turned up and then back to form a pole-piece 4 with its flat uppermost surface constituting the pole-face. Tightly fitting over, and riveted to, the rearward projecting end of the core 2 is a yoke 5 extending upwardly and forwardly along the top of the winding to within a short distance of the pole-piece 4.

The armature 6, which is almost but not quite flat when viewed edgewise (see Fig. 6), lies on the forward extension of the yoke 5 and bridges the gap between the yoke 5 and pole-piece 4.

Referring to Fig. 5, an opening is cut away in the rearward half of the armature 6, leaving a frame-like tail 7 carrying the lifting pins 8 for engagement with the moving spring in the pile-up. This tail 7 is bent slightly upwards with respect to the plane of the remainder of the armature (see Figs. 6 and 7). The bend between the forward and rearward halves of the armature is indicated in Fig. 5 by the line 9 on the upper side of the armature. Corresponding to this upper crease line, there is on the underside of the armature (see Figs. 6 and 7) a knife edge 10 which lies slightly below the level of the tail 7 and which therefore is able to constitute the pivot for the armature 6 as it rests upon the upper surface of the yoke 5 with its solid forward half overlying the pole-face on the pole-piece 4. Energization of the coil 1 causes the forward end of the armature 6 to be attracted downwardly to

2

the pole-piece 4, the armature turning about the knife-edge 10 so that the tail 7 rises and through the intermediary of the lifting pins 8 causes operation of the contacts. Thus the operating force and the contact load are applied on opposite sides of the pivot.

Referring now more particularly to Figs. 2, 3 and 4, together with Fig. 1, it will be seen that the spring-set is in two parts namely a root block 11 carrying all of the springs 12 and a buffer block 13 supporting the upper and lower springs at their free ends where they carry the contacts 14. These two parts are assembled together by means of a small bracket 15 located above the yoke 5 and pole-piece 4 and below the buffer block 13 and root block 11.

The root block 11 is a thermo-setting plastic, and the springs 12 constituting the contact-spring pile-up have their roots moulded in the plastic in the manner disclosed in the copending U. S. patent application Ser. No. 611,410, now abandoned. The buffer block 13 is of ceramic material and calls for no special comment.

Whereas in the relay disclosed in the copending U. S. patent application Ser. No. 546,545, now Patent No. 2,501,157, June 6, 1950, already mentioned, the flat armature is located by means of leaf springs extending normally across the pivoted axis and fixed to the armature on one side of the first and to the yoke on the other side, in the embodiment of the present invention now being described the leaf spring is omitted, the armature 6 being loose and being located by means of slots 16 in the armature leading off from the opening in the tail next to the knife-edge. These slots 16 are engaged by ears 17 on the bracket 15 that mounts the root block 11 and the buffer block 13 of the spring set assembly.

The root block 11 being moulded around the small bracket 15, and the buffer block 13 being attached to the bracket by a fusing process. This whole assembly is then placed on the coil assembly and secured by a screw 18 passing down into the yoke 5. As an alternative the screw may be replaced by a pin fixed in the yoke and secured by tin fusing to the ceramic at the top thus replacing the head of the screw by a tin fuse connection. This provides a complete design in which all parts are assembled without the use of screws and there is nothing to work loose under the conditions of vibration, shock, etc.

As in the copending U. S. patent application Ser. No. 546,545, now Patent No. 2,501,157, June 6, 1950, already mentioned, the gravitational moments of the masses of the moving parts are sub-

stantially balanced about the pivot 10. That is to say, the mass of the front portion of the armature produces at the pivot a moment which is just about equal to the moment produced by the mass of the tail part, together with the lifting pins, and the moving contact-springs down to their roots. By reason of this feature, a mechanical shock in the vertical direction (which is the worst case) produces equal and opposite accelerations about the pivot so that there is substantially no resultant torque that would cause improper operation or release of the armature.

As has been said above, it is one of the objects of this invention to provide a construction of relay which is resistant to adverse climatic conditions, especially the tropical conditions of high temperature and high humidity. Actually the requirements which this invention seeks to satisfy extend far beyond that: it is desired to have a relay which shall stand up to a temperature ranging from -40° C. to $+100^{\circ}$ C. with 100% humidity. It has been found by the present applicants that a source of failure in these extreme conditions lies with the lifting pins 8 when they are of the usual material; and they have therefore replaced this material by one more suitable, namely ceramic or vitreous material, or a thermosetting plastic, the pins 8 being secured to the armature 6 by cementing, fusing, moulding or other equivalent process.

An alternative arrangement for the mounting of the contact-spring pile-up in the root block 11 is shown in Fig. 8, which is a view onto the left-hand or forward end of a relay. Here the root block 11 is of ceramic material, and each contact-spring 12 is located in or on the ceramic block 11 by being received on a flat surface 19 thereof, and by being embedded in a setting material 20 adhering both to the spring and to the block. Each such flat is preferably overhung by adjacent portions 21 of the material on either side. The superficial extent of the bosses or the like between one flat and another and including the over-hanging function provides adequate insulation between the several springs.

In yet another alternative arrangement for the mounting of the contact-spring pile-up in the root block 11, the root block is of ceramic, as in Fig. 8, but is of different shape. Reference to Fig. 9, which is a similar view to Fig. 8, shows the ceramic root block 11 formed with two serrated holes 22 through which the springs 12 extend, being spaced and located by the serrations. When the springs have been inserted, the holes are filled by an injection process with one of the relatively high temperature high insulating materials such as a synthetic resin or one of the self hardening materials such as plaster of Paris.

This filling completely encloses the spring root to exclude dust, moisture, etc.

What is claimed is:

1. An electromagnetic relay comprising a winding, a core extending through said winding and having front and rear upturned portions, a forward extension on said rear upturned portion, an armature having a front end overlying said front upturned portion, said armature being pivoted at an intermediate point on said forward extension, a fixed support overlying said armature and having integral projections thereon for positioning said armature thereto, spring mounting means on said support, a plurality of contact springs carried by said mounting means, and operating means on the rear end of said armature engaging at least one of said contact springs in such manner that said contact spring tends to pivot said armature so as to lift said front end off said front upturned portion, energization of said winding acting to pivot said armature in the opposite direction.

2. An electromagnetic relay according to claim 1 wherein the gravitational moments of the masses of said armature, said operating means and the contact spring or springs engaged thereby are balanced about said intermediate point.

3. An electromagnetic relay according to claim 1 wherein the part of the armature to the front of said intermediate point is a solid piece of material and the part of the armature to the rear of said intermediate point is in the form of a frame-like tail.

STANLEY HERBERT TOWNER.
